UNITED STATES PATENT OFFICE

94,394

DESIGN FOR A RADIATING HEATER CASING

Louis D. Summers, Sr., and Louis D. Summers, Jr.,
Chicago, Ill., assignors to Cole's Hot Blast Man-
ufacturing Company, Chicago, Ill.

Application November 5, 1934, Serial No. 53,900

Term of patent 3½ years

To whom it may concern:

Be it known that we, Louis D. Summers, Sr., and Louis D. Summers, Jr., citizens of the United States, and residents of the city of Chicago, county of Cook, and State of Illinois, have invented a new, original, and ornamental Design for a Radiating Heater Casing, of which the following is the specification, and reference being had to the accompanying drawing, forming a part thereof:

Figure 1 is a perspective view of the radiating heater casing of our invention.

Figure 2 is a front elevation of our heater.

Figure 3 is a side elevation of our heater.

We claim

The ornamental design for a radiating heater casing as shown.

LOUIS D. SUMMERS, SR.
